US00D890098S

(12) **United States Design Patent** (10) Patent No.: **US D890,098 S**
 Byrne et al. (45) Date of Patent: ** Jul. 14, 2020

(54) **ELECTRICAL CONNECTOR**

(71) Applicants: **Norman R. Byrne**, Ada, MI (US);
Shane Rogers, Rockford, MI (US);
Timothy J. Warwick, Sparta, MI (US);
Daniel P. Byrne, Lowell, MI (US);
Marc A. Mitchell, Belmont, MI (US);
Randell E. Pate, Jenison, MI (US)

(72) Inventors: **Norman R. Byrne**, Ada, MI (US);
Shane Rogers, Rockford, MI (US);
Timothy J. Warwick, Sparta, MI (US);
Daniel P. Byrne, Lowell, MI (US);
Marc A. Mitchell, Belmont, MI (US);
Randell E. Pate, Jenison, MI (US)

(**) Term: **15 Years**

(21) Appl. No.: **29/607,301**

(22) Filed: **Jun. 12, 2017**

(51) LOC (12) Cl. **13-03**

(52) U.S. Cl.

USPC **D13/133**

(57) **CLAIM**

The ornamental design for an electrical connector, as shown and described.

DESCRIPTION

FIG. 1 is a front perspective view of an electrical connector showing our new design;

FIG. 2 is a rear perspective view thereof;

FIG. 3 is a top plan view thereof;

FIG. 4 is a bottom plan view thereof;

FIG. 5 is a right side elevation thereof;

FIG. 6 is a left side elevation thereof;

FIG. 7 is a rear elevation thereof; and,

FIG. 8 is a front elevation thereof.

In the drawings, the broken lines depict unclaimed subject matter only, and form no part of the claimed design.

1 Claim, 2 Drawing Sheets
